UNITED STATES PATENT OFFICE.

ERNIE ADAMSON, OF ATLANTA, GEORGIA.

ACETYLENE-GAS GENERATOR.

1,314,780.

Specification of Letters Patent.

Patented Sept. 2, 1919.

Application filed August 14, 1918. Serial No. 249,774.

To all whom it may concern:

Be it known that ERNIE ADAMSON, a citizen of the United States of America, residing at Atlanta, in the county of Fulton and State of Georgia, has invented certain new and useful Improvements in Acetylene-Gas Generators, of which the following is a specification.

The present invention relates to improvements in acetylene gas generators of the ebb and flow, or "kissing" type wherein the generators contain carbid to which the water is admitted by an ebb and flow movement produced by pressure of gas in the generator.

The primary object of the invention is the provision for an efficient, portable, self contained, generator for acetylene gas, that is compactly arranged and in which the different parts are easily accessible, rendering the device particularly simple in construction and facile in its operation. The invention consists in certain novel combinations and arrangements of parts as will be hereinafter described and claimed.

In the accompanying drawings there is one complete example, and a modification thereof, in which the physical embodiment of the invention is illustrated, constructed and arranged according to the best mode so far devised for the practical application of the principles of the invention.

Figure 1 is a vertical sectional view of the preferred form of the invention.

Fig. 2 is a transverse sectional view at line 2—2 of Fig. 1.

Fig. 3 is a similar view at line 3—3 of Fig. 1.

Fig. 4 is a sectional view of a modification showing a collapsible device embodying the principles of the invention.

Fig. 5 is a transverse sectional view at line 5—5 of Fig. 3.

Fig. 6 is a similar view at line 6—6 of Fig. 4.

In the preferred form of the invention as illustrated in Figs. 1, 2, and 3, a tank or outer cylindrical casing 1 is provided, preferably of metal and cylindrical in shape, being open at the top and provided with a closed bottom 2. The device is of a size to be readily portable, and may be carried by hand, by means of the bail or handle 3, and the open upper end of the tank is closed by a lid or cover 4 to prevent splashing or loss of water through the top. In the upper end of the tank the water chamber or reservoir

W is indicated, and in the lower part of the tank is located the gas bell 5 having an open bottom and closed top 6, the gas chamber being designated G.

The gas bell is retained in the tank through the instrumentality of an inverted U-shaped yoke 7, the legs of which are attached to the outside of the cylindrical bell, and the yoke projects upwardly a suitable distance to engage under the diametrically arranged angle brackets 8 attached to the inner wall of the cylindrical tank, the yoke being of metal possessing sufficient resiliency to permit forcing the yoke under the brackets to hold the bell in position.

Within the bell is inclosed a third cylindrical member or receptacle 9, open at both ends, and provided with three foraminous partitions, as 10, 11, and 12, the first designed to support the carbid C in the upper part of the receptacle, the second or intermediate partition designed to catch the carbid as it falls from the bottom of the carbid supply C, and permit the broken carbid, while on this intermediate partition, to be fully and completely decomposed and disintegrated before passing through this partition and falling, in the form of ashes upon the plate 13 on the partition 12 at the bottom of the receptacle.

A pair of lateral openings 14 are provided in the walls of the receptacle, just below the top partition or carbid support, and about in the same plane with the intermediate partition 11, so that water may pass through these two openings or ports from the lower part of the bell to the interior of the receptacle, and contact with the carbid through the foraminous partition or support 10.

The carbid receptacle is centered and supported within the bell by means of a number of braces 15, that are preferably made of resilient metal in order to frictionally engage the inner walls of the bell and hold the receptacle stable, and one of these braces also supports an oil vessel or chamber 16, located at the exterior of the receptacle within the bell and designed to contain oil that will flow from its open top and form a layer on the top of the water as it rises in the bell and contacts with the carbid so that the carbid comes in contact with water under the oil, thus preventing generation of steam and premature breaking down of the carbid.

The receptacle stands upon the bottom of the tank, and through the pins 17, 17 which project diametrically from the exterior of the receptacle, and the bayonet notches 17' 5 in the lower edge of the bell, the bell is held elevated a sufficient distance above the bottom of the tank to permit circulation of the water. A weight 18 in the top of the receptacle provides for a continuous feed of 10 the carbid, and openings 19, 20 and 21 in the wall of the receptacle provide for circulation of air to the carbid, and of water at the bottom of the receptacle and bell.

The gas outlet pipe 22, it will readily be 15 seen is U-shape with one leg opening in the gas chamber G, and the other leg extends up through the top or cover 4, and is provided with a valve 23, and a nozzle end to which may be attached the usual gas tube or 20 hose.

With the parts as shown in Fig. 1, but with the valve 23 closed, water is poured into the tank, occupying the tank and rising up to the level above the top of the open oil 25 cup 16, whereupon the closed valve 23 is opened to permit air to escape from the gas chamber, and the water level rises, with the layer of oil thereon, until the water contacts with carbid through the foraminous partition 30 10, and gas is generated and rises to the chamber G of the bell. As the carbid breaks off the bottom of the supply, it falls upon the intermediate partition 11 where it is further and completely decomposed and 35 disintegrated so that the ashes fall through this partition 11 and fall through the water to the plate 13. As the gas is consumed the pressure is decreased and consequently the water ebbs and flows, with the changes in 40 pressure, and continually replenishes the gas supply, which is of course controlled through the valve 23.

The lumps of carbid in the holder that are in immediate contact with the water, are 45 pressed down by reason of the weight of the member 18 in the top or upper end of the holder, and the surfaces of the carbid before being acted on by the water are first submerged in the oil, the lumps of carbid then 50 being forced or fed through the grate 10 and the oil layer to the water below. Water is fed to the carbid and regulated by the pressure of the water column balanced against the pressure of gas in the bell, and 55 as the water recedes from the carbid and rises alternately it will be apparent that the oil intermittently passes and repasses the grate 10 and the bottom surface of the carbid supply, thus coating the lumps of carbid 60 with oil.

The "layer" of oil is much thicker than a "film" or "coating" of oil on the surface of the water, and this layer of oil not only prevents evaporation of the water, while the 65 generator is standing idle, but at the same

time causes the automatic treatment of the carbid with the oil while the generator is in operation. The layer of oil and the water also co-act to prevent high temperature of the water in the tank while the generator 70 is in operation, and they maintain a low temperature at the point of contact of the water with the carbid. The large volume of water conducts away the heat units from the bell, and the gas, when passing through the 75 oil and water is also reduced in temperature. As the gas passes through the oil and water it is washed of most of its impurities, thus providing a comparatively pure medium in 80 the generator without the further necessity of employing a separate washing and filtering device.

It will be seen that the amount of carbid attacked by the water is relatively small, compared with the volume of water and oil 85 in immediate contact therewith, and the arrangement of the outlet pipe in the generator so as to direct the current of newly generated gas away from the carbid in the holder prevents the absorption by the carbid of any 90 vapor that may arise with the generated gas.

In Figs. 4, 5, and 6, a modification in the form of a collapsible device is shown, where-in in the tank 1^a is made of flexible material as cloth or canvas, as is also the flexible bell 5' 95 which is anchored to the bottom of the tank by hooks 6', and the weight 18', which is indicated as smaller than the weight 18 indicates the manner of varying the pressure of carbid by using different weights. The gas pipe 22' is attached to the receptacle 9 and opens in the gas chamber G, and at its lower end has a nozzle for attachment of the flexible tube 25 that is equipped with the usual valve 23. The entire apparatus may be carried by means of the handle 26 which is firmly secured to the top of the water tank or bucket 1^a and this collapsible bucket is held distended by means of the foldable braces or stays 24 arranged within the upper 100 part of the bucket or canvas tank and pivoted at their lower ends about on a line with the top of the receptacle 9. It will readily be seen that the collapsible form of the device as illustrated in Figs. 4, 5, and 6, provides a generator that may be compactly arranged to occupy comparatively small space when not in use, and which may, with facility, be made ready for use, and is then efficient in producing the gas required, as described in the first and preferred form. 115

By means of the weight 18 the gravity feed is enhanced for the carbid, and by arranging the carbid within the receptacle in the manner shown, the generated gas in the 120 chamber does not contact with the carbid, but is drawn off outside the carbid holder or receptacle, and utilization of the auxiliary partition 11 and ash supporting partition 12-13, a maximum amount of gas is 130

obtained from the carbid which is at all times submerged after falling through the supporting partition 10.

Claims—

5. The combination with the tank containing water, of a bell therein having an inverted U-shaped yoke of resilient metal and a pair of retaining brackets on the interior of the tank co-acting with the yoke, a
10 removable carbid holder within the bell, said holder having means for supporting the bell above the bottom of the tank.
15. The combination with the generating tank containing water and the bell therein, of a carbid holder within the bell having ports opening into the bell, and a foraminous partition for supporting the carbid, and a weight located in the holder on top of the carbid to furnish a continuous feed of
20 carbid for the water.
25. The combination in a gas generating device comprising the tank and bell, of a carbid holder within the bell and an oil container supported between the holder and bell having an outlet below the contact portion of the carbid supply within the holder.
30. The combination in a generator as described with a bell and a carbid holder enclosed therein and formed with water ports beneath the carbid supply, and an oil con-

tainer between the bell and holder with an opening below the contact portion of the carbid supply within the holder.

5. The combination with the tank having retaining brackets, of a carbid holder supported on the bottom of the tank and having water ports in its wall, a foraminous partition in the holder above the ports for carbid and a weight on the carbid, an intermediate foraminous partition in the holder and a partition at the bottom of the holder to receive ashes, a bell and means for supporting the bell from the holder, and a brace on the bell engaging the brackets, as described. 35

6. The combination in an ebb and flow gas generator having a tank and bell and a layer of oil covering the water in the bell, of a carbid holder within the bell comprising a series of foraminous partitions including the uppermost forming a carbid support and feeder for lumps of partly decomposed carbid and a lower receiving partition of smaller mesh to permit passage of thoroughly decomposed particles of carbid, a weight on top of the carbid supply in the holder, and said holder having ports below the uppermost partition. 40 45 50 55

In testimony whereof I affix my signature.
ERNIE ADAMSON.
